UNITED STATES PATENT OFFICE.

ROBERT E. McCLELLAND, OF SPRINGFIELD, ILLINOIS.

DESIGN FOR A CALCULATOR-CASING.

46,933.

Specification for Design.

Patented Feb. 9, 1915.

Application filed June 3, 1914. Serial No. 842,786. Term of patent 3½ years.

To all whom it may concern:

Be it known that I, ROBERT E. McCLELLAND, a citizen of the United States, residing at Springfield, in the county of Sangamon and State of Illinois, have invented a new, original, and ornamental Design for Calculator-Casings, of which the following is a specification, reference being had to the accompanying drawing, forming part thereof.

Figure 1 is a front view of a calculator casing embodying my invention; and Fig. 2 is a vertical section on the line X. X of Fig. 1.

The invention primarily resides in the ornamental contour of the casing, comprising a figure of rectangular outline varied by mixtilineal angles joined by a curved line as shown.

It also subsists in a border line substan-

tially following the contour of the casing and inclosing a main field or area bounded by a figure having six internal right angles and four mixtilineal angles and also inclosing a corner panel having three internal right angles and two mixtilineal angles; an ornamented line within the field and substantially following the border line inclosing the main field; and an ornamented line within the corner panel and substantially following the border line inclosing the corner panel.

I claim:

The ornamental design for a calculator casing, as shown and described.

ROBERT E. McCLELLAND.

Witnesses:

THEO. F. KNOLL,
ANNA FOBBE.
